United States Patent Office

Des. 186,178

Patented Sept. 22, 1959

186,178

SKATE CHASSIS

Clarence R. Reynolds, Cleveland, Ohio, assignor to The Cleveland Skate Co., Inc., Cleveland, Ohio, a corporation of Ohio

Application May 27, 1958, Serial No. 51,100

Term of patent 14 years

(Cl. D34—14)

Fig. 1 is a top perspective view of my design, while Fig. 2 is a bottom perspective view of the same.
I claim:

The ornamental design for a skate chassis, as shown.

References Cited in the file of this patent

UNITED STATES PATENTS

D. 143,983	Miller	Feb. 26, 1946
D. 160,110	Normandin	Sept. 12, 1950
D. 162,129	Coldwell	Feb. 27, 1951
2,424,783	Ware	July 29, 1947